APPARATUS FOR SELECTING METAL CHECKS

Application filed September 18, 1929. Serial No. 393,495.

This invention relates to an improvement in coin or check selecting mechanism for use in connection with vending machines, coin changing machines, et cetera, and the main 5 object of this invention is to provide improved means for selecting coins or checks so as to cause acceptance only of coins having definite properties of electrical conductivity.

Our invention comprises an improved apparatus for coin selection in which the selection of the coin is effected by deviation of the coin from the path in which it is falling freely under the action of gravity, such deviation being due to the action of the magnetic field through which the coin is caused to pass while so falling freely, the action of the magnetic field on the coins or checks of electrically conducting material being such as to deflect the coin or check from the path 10 it would take under the action of gravity alone and the deflection in the path so produced being utilized in the selection of the coin.

The accompanying drawing illustrates an 25 embodiment of our invention and referring thereto:

Figure 1 is a vertical section of the selecting means.

Figure 2 is a section of line 2—2, Figure 1. 30 In the accompanying drawing we have shown only that part of a check selecting mechanism which is required for carrying out our present invention, it being understood that the same may, if desired, be used 35 in connection with various other selecting devices for causing rejection of checks or coins according to weight, thickness, et cetera, the purpose of the present invention being only to select the coin or check according 40 to its correspondence to a definite standard of electrical conductivity, namely the electrical conductivity of the proper coin to be selected.

The apparatus comprises a casing having 45 two side plates (1), spaced apart by spacing members (2 and 3) so as to provide between the said side plates a space slightly greater in thickness than the thickness of coins to be selected. At its upper portion said casing 50 may be provided with a coin chute (4)

through which the coins or checks to be selected are admitted to the selecting device, it being understood that this coin chute may lead directly from a coin opening through which the coin or check can be inserted, or 55 may lead from any other suitable selecting means for subjecting the coin or check to a preliminary selecting operation of any kind. The coin chute (4) or the portion thereof directly adjacent to the selecting means hereinafter described is preferably vertical or such as to provide for approximately vertical movement of the coin or check in passing to the selecting means and the walls of said coin chute are spaced sufficiently far apart to enable the coin or check to fall freely into position for the operating of the selecting means.

A magnet (6) which may for example be a permanent magnet, is provided adjacent to 70 the said casing and has pole pieces (7) extending on opposite sides of the casing and projecting through the side plates (1) as shown at 7', the inner ends of the pole extension (7') being spaced apart at such a 75 distance as to permit the coins or checks to fall between the same but presenting a strong magnetic field through which the coin must pass. The pole piece members 7' are preferably located so that their centers are at one 80 side of the path of the center of the coins or checks descending from the coin chute (4), so that the magnetic field therebetween is asymmetric with respect to the center line of said path. The spacing members (2) of 85 the casing are sufficiently far apart to permit free movement of the coin in a plane parallel to the side plates (1), and therefore parallel to the plane of the coin or check.

Below the magnetic selecting means above 90 described, suitable means are provided for selecting the coin or check according to its path or trajectory after leaving said magnetic selecting means. For this purpose we may provide, for example, an anvil or impact member (9) having upper face (9') in position to receive a coin of proper character, and rebound same in a definite path. A partition (10) may be provided between the anvil (9) and one end wall of the casing, the 95 100

coin selecting chamber being divided by members (9) and (10) into a delivery chute (11) for proper coins, and delivery chutes (12 and 13) for spurious or improper coins or checks.

The operation of the above described device is as follows:

- A coin or check supplied to the coin chute falls therein under the action of gravity and
- 10 on leaving the lower portion of said chute is out of contact with the side walls (2 and 3) of the casing or other lateral obstructions so as to permit the coin to move freely under the action of applied forces as hereinafter
- 15 described, in any direction parallel to the plane of the side plates (1). Assuming, for example, that the proper coin is of the dimensions shown in dotted lines at "a", the pole piece members (7') are preferably made
- 20 considerably smaller than the diameter of the coin and located at one side of the path of the center of the coin as it descends from the coin chutes (4). As the coin or check passes through the magnetic field between the pole
- 25 piece members (7') electrical currents (eddy currents) are generated in that portion of the coin which is between the pole pieces and with the result that a mechanical force is produced on that portion of the coin tending
- 30 to retard the downward motion of such portion of the coin. Inasmuch as retardation is concentrated at a portion of the coin at one side of the center, the effect of gravity and of the momentum of the coin tends to swing
- 35 the coin around such retarded portion as indicated by the arrows. If the coin is of proper conductivity, size and weight, it will follow a path such as shown by the full line arrows, the diversion of the path of the coin
- 40 being such as to cause it to impinge on the anvil face (9') and be rebounded therefrom as indicated to the acceptance compartment (11). If the coin is of unduly high conductivity, for example, copper, it may follow a
- 45 course such as shown by broken line arrows and be thereby diverted to a rejection compartment or chute (13) as shown at "b". If the coin or check is of insufficient conductivity or in case of a check, being of insulating material it may fall vertically from
- 50 the coin chute through the means described without being materially affected thereby and in that case will pass through the rejection compartment or chute (12), as indicated at "c". It will be seen, therefore, that the deflection of the check is caused by the asymmetric position of the magnetic field with respect to the path of fall of the center of the checks, and that the extent of such deflection, and consequently the separation of the checks from one another, is dependent upon the electrical conductivity thereof.

It will be understood that suitable means will be provided for rejecting any slugs of

65 iron or other strongly paramagnetic mate-

rial before they reach the selecting means described, such rejecting means not being shown as they are well known in the art, this being necessary for the reason that such slugs would be liable to stop in the magnetic field and clog the mechanism.

We claim:

1. An apparatus for selecting coins or checks comprising casing means having spaced side walls defining a space through which a coin or check is permitted to fall freely in its own vertical plane, said space being extended horizontally in said plane so as to permit free movement of the coin or check in said plane, a magnet having poles disposed adjacent said casing means and so positioned as to create a magnetic field across the path of a coin or check falling in said space and asymmetrical with respect to the center line of said path, so as to cause deviation in the path of movement of a coin or check of conducting material by the action of said magnetic field thereon, and means disposed in said vertical plane below said magnetic poles for effecting selection of a coin or check according to the path of movement thereof after passage of the coin or check through said magnetic field.

2. An apparatus for selection of coins or checks comprising casing means having spaced side walls defining a space through which a coin or check is permitted to fall freely in its own vertical plane, said space being extended horizontal in said plane so as to permit free movement of the coin or check in said plane, chute means for delivering a coin or check to said space so as to cause the same to fall in a certain path, a magnet having poles disposed adjacent said casing means and so located that the magnetic field therebetween crosses said path of the check and is concentrated at a position lying at one side of the center of said path so as to cause retardation of that side of the coin or check, and consequent deviation of the path thereof, in accordance with the electrical conductivity of such coin or check, and means for effecting selection of the coins or checks according to the difference in the path of movement thereof after passage through said magnetic field.

3. An apparatus for selection of coins or checks comprising casing means having spaced side walls defining a space through which a coin or check is permitted to fall freely in its own vertical plane, said space being extended horizontally in said plane so as to permit free movement of the coin or check in said plane, chute means for delivering a coin or check to said space so as to cause the same to fall in a certain path, a magnet having poles disposed at opposite sides of said space and so positioned that the line joining the centers thereof crosses said path at one side of the center of said path,

- and means disposed in said plane below said magnet poles for effecting selection of coins or checks according to the path of movement thereof after passage through said magnetic field.
4. An apparatus for selection of coins or checks comprising casing means having spaced side walls defining a space through which a coin or check is permitted to fall freely in its own vertical plane, said space being extended horizontally in said plane so as to permit free movement of the coin or check in said plane, a magnet having poles adjacent said casing means and so disposed as to create a magnetic field across said space, chute means for delivering a coin or check to said space in such manner as to cause the same to fall freely through said space in a path whose center passes at one side of the center of said magnetic field between said poles, and means for effecting selection of the coins or checks according to the path of movement thereof after passage through said magnetic field.
- 25 In testimony whereof we have hereunto subscribed our names this 10th day of Sept. 1929.
